DOUBLE VANE IMPELLER

Oystein Jacobsen, Montgomery County, Ohio, assignor to The Duriron Company, Inc., Dayton, Ohio, a corporation of New York

Application August 12, 1940, Serial No. 352,237

4 Claims. (Cl. 103—103)

This invention relates to centrifugal pumps of the open runner type, and in particular to such pumps for pumping corrosive fluids, or other liquids containing solid matter in suspension.

The primary object of this invention is to provide an open runner centrifugal pump with means for preventing flow of the pumped fluid along the drive shaft and through the packing thereof.

Another object is to provide a centrifugal pump of the character mentioned, having an impeller mounted on a shaft supported within a casing, this impeller having a dual pumping function, one consisting of pumping the main body of fluid or fluid-like material from the pump intake chamber, and the other consisting of pumping the leakage fluid or fluid-like material from the chamber adjacent the packing so as to prevent the leakage of the fluid or the fluid-like material along the shaft.

Another object is to provide a centrifugal pump having an impeller with dual sets of vanes, one set of vanes being of the open runner type and working on the centrifugal principle to pump one portion of fluid or liquid containing solid matter in suspension, the other set of vanes working upon the fluid-like material from another portion of the casing.

Another object is to provide a centrifugal pump of the open runner type having separate chambers within the impeller, one set of vane chambers opening into the pump intake chamber, the other set of vane chambers opening into a chamber adjacent the pump shaft packing.

Another object is to provide a centrifugal pump having a casing with an intake chamber and an impeller mounted on a shaft, with vanes secured at one side to the impeller and open at the other side to separate the interior of the impeller into two sets of vane chambers. The vane chambers of one set are directly connected to the pump intake chamber, the other set of vanes being closed at the side adjacent the open face of the impeller and connected to a chamber communicating with the pump shaft packing, and connected to the first set of vane chambers by means of restricted ports setting up a pumping effect within the second set of vane chambers.

From another aspect of the invention this action is enhanced by providing at least two apertures or ports in the vane chambers, which are connected to the chamber communicating with the pump shaft packing, one of these apertures opening into the adjacent vane passageway at the position of a zone of contraction which is normally formed at the inner ends of the vanes.

The invention will be better understood when the following specification is perused in connection with the accompanying drawings.

In the drawings:

Figure 1 is a central longitudinal section through a preferred embodiment of the pump of this invention.

Figure 2 is a perspective view looking at the edge of the impeller, with a portion broken away to show the improved vane chambers by which a jet action is produced on the leakage fluid.

Figure 3 is a sectional view of the pump taken along the line 3—3 of Figure 1.

Referring to the drawings in detail, the numeral 1 designates a heavy slightly conically shaped disc or plate forming the so-called back plate of the impeller. This plate is preferably made of an acid-resisting metal, such as silicon iron, in case it is desired to pump corrosive fluids either in liquid or partially liquid form. This back plate is provided with an outer flange portion 2, and there is a number of openings 3 cored through the plate to eliminate end thrust and to effect proper balance. The inner portion of the plate terminates in a hollow outwardly extending hub member 4, and intermediate this hub member and the flange portion 2 there is a conically shaped extension 5, cored out as indicated at 6 in order to allow entrance of liquid into impeller vanes 47.

The drive shaft 7 is provided with a shouldered portion 8 and a threaded portion 9, these portions being surrounded by a cast insert 10, preferably of bronze, firmly to secure the shaft to the impeller. Directly opposite the hub 4 and projecting inwardly there is a curved extension 11, forming with the hub 4 a compartment which readily receives the cast material 10 by which the shaft is held in place. There are discs 12 of packing material surrounding the shaft 7 and contained within a hollow hub extension 13 of the pump casing. The latter is provided with an inwardly projecting annular flange 14. A sleeve 14' surrounds the shaft 7, as seen in Figure 1.

The pump casing is constituted of a heavy casting having a side plate 15 at the left and a similar plate 16 at the right, the plate 15 being provided with outwardly extending surfaces 17, 18 as wearing surfaces for portion 2 and the hub portion 5, respectively, during operation of the pump. The side plate 15 has a peripherally

extending portion which forms a casing or chamber 19 (Figure 3) of a volute configuration. The impeller is adapted to rotate within this chamber. The size of the volute is considerably larger than the outside diameter of the impeller, and is drawn down to a discharge port 20 of approximately circular configuration. The latter terminates in an enlarged end 21 engaged by a clamping ring 22 for securing thereto a discharge conduit. The right-hand plate 16 is provided with an extending projection 23 having a surface 24 which bears against an adjacent surface 25 through a gasket 26.

The plates 15 and 16 are preferably formed of castings secured together in any suitable manner, and as illustrated there is provided a circular ring 27 which carries bolts 28, the latter extending through the ring and being secured to the pump support 29 by means of the nuts 30, 31 at each end of the bolt. It will be understood that the castings 15, 16 are constituted preferably of a corrosive-resisting metal, such as silicon iron, so that it is practically impossible to machine this metal, and the parts 15, 16 must be secured together by a clamping arrangement of which one type has been illustrated in Figure 1.

The casting 16 is provided with an intake extension 32 and an intake chamber 33, containing vanes 34 for preventing the swirling of the fluid or fluid-like material entering the pump. The outer end 35 of the intake extension 32 is enlarged and engaged by a clamping ring 36 for the purpose of securing thereto an intake conduit. The lower end of the casting 15 is provided with a drainage extension 37 having a drainage port 38, closed by a plate 39 and held in position by a U-bolt 40.

The vanes 41 of the impeller, as seen more clearly in Figure 3, are of a general spiral configuration, the direction of the spiral being dependent on the direction of rotation of the impeller. These vanes are preferably cast integral with the back plate 1 of the impeller, and except for two pairs of vanes as will be described presently, are open at the side facing the casting 16. Thus the vanes and the back plate constitute a so-called "open runner" form of impeller in that the vane compartments are, for the most part, entirely open at that side which faces the casting 16. These vanes preferably have a depth, i. e. that they extend to the right from the back plate such a distance that the right-hand edges of the vanes practically contact the left-hand surface of the casting 16, as seen in Figure 1. Obviously, the closer these vanes can approach the casting 16 without introducing excessive friction, the greater will be the volume of the liquid which will be subjected to the vane action and therefore the larger will be the output of the pump.

The passageways formed between the vanes may be broadly termed Venturi shaped in that there is a throat portion 42 (Figure 3) and also an outlet portion 43. Thus the vanes divide the interior of the impeller into alternately arranged vane chambers which at their inner ends open into intake passageway 44 communicating with the pump intake chamber 33. The outlet or peripheral portions 43 of the vanes are in communication with the volute chamber formed within the casting 15 so that as the impeller is rotated counter-clockwise, as in Figure 3, fluid is drawn through the intake chamber 33 and is discharged through the outlet port 20, depending on the speed of rotation of the impeller.

A study of the drawings will show that as the impeller is rotated there is a tendency for a portion of the fluid in the volute chamber, depending on the speed of the impeller, to leak through the space between the surfaces 2, 17, 5 also between the surfaces 18, 5 and possibly through any space which might exist at the flange 14, this fluid finally reaching the packing 12. Eventually the fluid will pass along the 10 shaft, even as far as the bearings (not shown). The latter are ordinarily made of a metal which permits corrosion by acids, so that this leakage fluid in time might utterly ruin the bearings.

It will be understood that there must be a 15 small space left between the bearing surfaces of the impeller back plate and the casting 15 in order to minimize friction, so that it is a fairly easy matter for leakage fluid to collect in the pocket indicated at 45, and thence to flow to 20 and collect in the pocket 46, where it is in a position to travel along the drive shaft and from there into the packing box. In accordance with one of the features of this invention there is provided a means for continually sucking 25 the leakage fluid from the pockets 45 and 46 and returning this fluid to the vane passageways, and eventually to the outlet passageway.

Referring now to Figure 3, it will be noted 30 that two pairs of oppositely positioned vanes 47 are connected together at their inner ends by a closure member 48. Each of these closure members is provided with a pair of apertures 49 and 50, respectively. The aperture 50 is preferably positioned at the lower side of the lower 35 vane 47 of each pair, its position being such, when the impeller is rotated, as to cause a jet action or suction effect on the fluid contained within the pocket 46. This leakage fluid in moving through the aperture 50 is caused to travel through the substantially closed compartment formed between the vanes 47, and to be expelled into the volute casing 19 together with the fluid that has passed through the remaining vanes 41. The aperture 49 is provided to increase the suction effect produced by the aperture 50.

The aperture 49 is positioned preferably in the 40 region of the so-called "zone of contraction" 51, which zones of contraction appear at the inner ends of the arcuate vanes. These zones are indicated in Figure 3, and represent positions at which the fluid, in moving around the ends of the vanes, causes a pocket representing a vacuum. As stated hereinbefore, the aperture 49 45 serves considerably to enhance the suction or evacuation effect exercised on the leakage fluid which passes from the pocket 46, through the opening 52 (Figure 3) and into the closed compartment. While I do not wish to be limited to any theory as to the cause of this enhancement, I believe that the aperture 49 serves to transfer 50 some of the suction effect present between the open vane compartment (between vane 47 and the adjacent vane 41) into the closed vane compartment. Thus as the vanes move counter-clockwise a vacuum tends to be created in the passageways between the vanes, and this vacuum can be transferred through the aperture 49 55 to assist the jet action effect exerted by the aperture 50. This enhancement of the suction effect on the leakage fluid is so great that it has been found necessary to close off only two pairs of vanes 47 in order to take care of all of the leakage fluid within the pocket 46, leaving the remaining vanes entirely open at their inner 60 65 70 75

ends to serve the normal pumping functions of the impeller.

It will be noted in Figure 3 that the vanes 47 do not have quite the same curvature as the open vanes 41. It has been found in practice that the vanes 47 should preferably have less sweep than the remaining vanes so that the vanes 47 take on a shape which might broadly be termed S-shape. In order to prevent any swirling or eddy current action between the outer tips of the vanes 47 and the next vane 41 in sequence (depending on the direction of rotation) it has been found desirable to introduce a pair of blades or vanes 53 which serve merely to maintain the volute or arcuate direction of the fluid as it leaves the impeller.

In case the pump is employed for pumping fluids containing solid materials which might have an abrasive effect, it is apparent that the space between the right-hand surfaces of the vanes 41 and the left-hand surface of the casting 16 will become greater and greater during operation of the pump. It will be understood that it would be impractical to take up this wear by moving the impeller as a body to the right, because in that case greater spaces will be left at the surfaces 2, 17, also between the surfaces 18 and 5 and at the flange 14 to permit considerable flow of leakage fluid into the packing box. While small spaces between the right-hand surface of each vane 41 and its adjacent casting surface have little or no effect on the output of the pump, it has been found that these small spaces greatly affect the efficiency with which the compartments contained between the vanes 47 perform their suction effect on the leakage fluid, and the facility with which this fluid is moved through the compartments into the volute casting 19.

In accordance with the present invention there is provided a plate or cover 54 over each compartment formed between the vanes 47, this cover serving the purpose of isolating the liquid flowing through the vane compartments 47 from any fluid which tends to pass between the right-hand surfaces of the vanes and the casting 16. This cover is preferably cast integral with the vanes 47 so that the compartment between the vanes is closed on the four sides, and also at the inner end except for the openings 49, 50, but is completely open at its outer or peripheral boundary. The compartment between the vanes 47 including the openings 49, 50 can be readily formed by a coring-out operation so that there are no practical difficulties in the fabrication of the two compartments through which the leakage fluid is caused to flow. It will be noted that, regardless of the amount of wear which takes place at the right-hand surfaces of the vanes 41, 47 (as seen in Figure 1), due perhaps to abrasives in the fluid, none of this fluid is able to enter the closed compartments or in any other manner deleteriously affect the passage of leakage fluid from the pocket 46, through the opening 52 and thence into the closed compartments. The closed compartments are therefore free of all fluid or fluid-like material except such fluid as is drawn through the openings 49, 50, thus causing the closed compartments to exercise a great suction effect on the leakage fluid which collects in the pocket 46.

It will be understood that I desire to comprehend within my invention such modifications as come within the scope of the claims and the invention.

Having thus fully described my invention, what I claim as new and desire to secure by Letters Patent is:

1. A fluid pump of the centrifugal type comprising a casing and an impeller adapted to rotate in the casing, said impeller including a back plate, vanes secured thereto to leave open passageways between the vanes and the side of the casing cover opposite to said back plate, means for draining the leakage fluid which collects between the back plate of the impeller and the adjacent surface of the casing, said means including a closure member across the inner ends of at least one pair of vanes but less than the total number of vanes to form a compartment closed at the inner end and open at the outer end, an opening in said closure member communicating with the space between the back plate of the impeller and the casing through a passageway located within the compartment and closely adjacent the opening in the closure member whereby leakage fluid is caused to flow through said passageway into the compartment and out of the impeller through the open end of the compartment, and a plate spanning each pair only of said vanes which are interconnected by a closure member and at the side opposite said back plate.

2. A fluid pump of the centrifugal type comprising a casing containing an impeller formed of a plurality of vanes secured to a back plate to leave open passageways between the vanes and the side of the casing opposite said back plate, an inlet passageway leading to the center of the impeller and communicating with the passageways between the vanes, an outlet passageway leading from the periphery of the impeller, said impeller being rotatably mounted adjacent to a wearing plate, and means for draining the fluid which passes between the impeller and the wearing plate, said means including a closure member across the inner ends of at least one pair of vanes but less than the total number of vanes to form a compartment which opens into the outlet passageway, said inlet passageway having a larger area than the vane passageways whereby a zone of contraction is normally produced at the junction between the inlet and vane passageways, said closure member having an aperture which opens into the adjacent vane passageway at the position of said zone of contraction and communicates with the space between the impeller and the wearing plate through an opening located within the compartment and closely adjacent the aperture in the closure member, said compartment being completely closed except for said aperture and opening at one end and the opening at the other end which leads into the outlet passageway.

3. A fluid pump of the centrifugal type comprising a casing containing an impeller formed of a plurality of vanes secured to a back plate to leave open passageways between the vanes and the side of the casing opposite said back plate, an inlet passageway leading to the center of the impeller communicating with the passageways between the vanes, an outlet passageway leading from the periphery of the impeller, means including a shaft and a stuffing box for rotatably mounting said impeller, means for preventing fluid from leaking along the shaft into the stuffing box, said means including an apertured closure member across the inner ends of at least one pair of vanes but less than the total number of vanes to form a compartment which opens into the outlet passageway, said means also in-

cluding an opening in the impeller in the region of the stuffing box, said opening being located within the compartment closely adjacent the aperture in said closure member and communicating therewith whereby a suction effect is introduced by said aperture to cause the leakage fluid to flow through said opening in the impeller and to be expelled at the periphery of said compartment, said inlet passageway having a larger area than the vane passageways whereby a zone of contraction is normally produced at the junction between the inlet and vane passageways, means for increasing the suction effect on the leakage fluid in said compartment, said means including a second aperture in said closure member positioned in the region of said zone of contraction, and a plate extending across said pair of vanes at a position opposite said back plate whereby the compartment is closed on four sides and is closed at one end except for the pair of apertures but is open at the end which leads into the outlet passageway.

4. A fluid pump of the centrifugal type comprising a casing, an impeller adapted to rotate in said casing and having a back plate, a plurality of vanes secured to said back plate, an inlet passageway leading to the center of the impeller

and communicating with the passageways between the vanes, an outlet passageway leading from the periphery of the impeller, a closure member across the inner ends of at least two pairs of adjacent vanes, the pairs being diametrically positioned with respect to one another but constituting less than the total number of vanes, the remaining vanes having their inner ends left open, the vanes with the closed inner ends having top plates which are spaced from said back plate to form closed compartments which are open only at the outer ends and closed at the inner ends, the remaining vanes being provided with only said back plate whereby the compartments formed thereby are open at one side, also open at the inner and outer ends, said closure member having an aperture which communicates through an opening in the back plate with the space between the back plate of the impeller and the casing to cause a suction effect on the leakage fluid as the impeller is rotated whereby said fluid is caused to pass through the closed compartment into the outlet passageway, said opening being contained within the closed compartment and closely adjacent the aperture in the closure member.

OYSTEIN JACOBSEN.
